UNITED STATES PATENT OFFICE.

STILLMAN HOUGHTON, OF WORCESTER, MASSACHUSETTS.

IMPROVEMENT IN HOOP-SKIRT WIRE.

Specification forming part of Letters Patent No. 55,495, dated June 12, 1866.

To all whom it may concern:

Be it known that I, STILLMAN HOUGHTON, of the city and county of Worcester, and Commonwealth of Massachusetts, have invented a certain new and useful Improvement in Skirt-Hoop Wire; and I do hereby declare that the following is a full, clear, and exact description of the same, reference being had to the accompanying drawings, forming a part of this specification, in which—

Figure 1 represents a piece of steel wire with my improvement applied thereto, and Fig. 2 represents a longitudinal section of a piece of steel wire with my improvement applied thereto.

The common mode of preparing the skirt-hoop wire for use is to take the flattened wire, as seen at A, and cover it with some fibrous material, the most common mode being to braid cotton yarn or thread upon the wire, as seen at *a* in the drawings. There are some objections to wire so covered, owing to the fact that the fibrous material is liable to wear off, especially from the lower or bottom hoops. Again, with hoops thus made, when broken, the ends at once protrude, and are often a source of great inconvenience to the wearer.

My improvement consists in applying a braided plated-wire covering on top of the fibrous covering, as seen at *b*. This braided

plated-wire covering not only adds much to the appearance of the hoop, but securely protects the fibrous covering from wear, while at the same time preventing the protrusion of the ends of the wire A, should the wire become broken while in use. Again, the wire A, when so covered, is not so liable to break, owing to the fact that the braided-wire covering forms an elastic guard or casing to such an extent as to prevent any short bending or curvatures in the wire A, which is the main cause of its breaking after being made into hoops for skirts.

It will be observed that the diamond-shaped meshes formed by the braiding of the plated wire give to the finished hoop a beautiful appearance, while, in case one of the plated wires becomes broken, it cannot unbraid, but is retained in position.

Having described my invention, what I claim therein as new, and desire to secure by Letters Patent as an improved article of manufacture, is—

Skirt-hoop wire first covered with a fibrous material, and then a braided plated-wire covering or casing applied thereto, substantially as shown and described.

STILLMAN HOUGHTON.
